UNITED STATES PATENT OFFICE

LAMBERT VON REIS, OF HERZOGENRATH, GERMANY, ASSIGNOR, BY MESNE ASSIGNMENTS, TO THE AMERICAN BICHEROUX COMPANY, A CORPORATION OF DELAWARE

MEANS FOR CUTTING SHEET GLASS

Application filed July 20, 1926, Serial No. 123,763, and in Germany July 27, 1925.

This invention relates to a method and a device for cutting sheet glass while still in plastic condition. The method and the device are more particularly designed to be used in the manufacture of sheet glass by means of a rolling machine comprising at least two rolls, but they may also be used in all other methods of manufacturing sheet or plate glass.

An embodiment of the subject-matter of the invention is illustrated in the accompanying drawings in which:

Fig. 1 is a side elevation of the cutting device,

Fig. 2 is a transverse section of the device,

Fig. 3 is a plan view,

Fig. 4 is a view similar to Fig. 3 showing the position of a drop knife during the cutting operation, and

Fig. 5 is another view similar to Fig. 3 showing the position of a drop knife when raised after the cutting operation. Fig. 1^a is a detail side elevation.

are travelling tables designed to receive the sheet or plate glass from a rolling machine and convey it, for instance, to an annealing kiln. b is a drop knife arranged for swinging and shifting motion on a horizontal shaft c arranged to extend parallelly of the track of the tables a. d is a roller carried by an arm d' of the knife b and designed to guide the knife after the cutting over an inclined plane e. f is a weight connected by a cable f' with the knife b and serving to retract the knife. g are stops arranged at a side of the tables near their forward ends. h is the space or gap existing between two tables each. The knife b is adapted to drop into this gap when executing its cutting operation. The tables a are provided at their longitudinal edges

with rails m on which runs a roller i carried by an arm i' of the knife and designed to hold the knife in its lifted position. The shaft c is mounted in bearings k of a base l. When there is no table below the knife b, same is held in its lifted position by means of a clutch coupling n which is more fully described hereinafter. p is a member pivotally carried by each table and designed to bridge the gap between the tables when same are being re-

automatically swing the members p into bridging position during the said return travel of the tables.

The glass rolling machine, which forms no part of this invention, is not illustrated in the drawings.

The operation of the described device is as follows: The glass rolling machine is supposed to be arranged at the left hand end of the tables shown on the drawings. As soon as the rolling machine begins to roll out a sheet of glass, the tables a which are arranged below the machine start their travel in the direction of the arrow indicated in Fig. 3. While in movement they receive the glass sheet formed on the machine and carry it along with them. When the tables are moving forward the knife b rests by its roller i on the rails m and is held by the same in its lifted position. The knife b is pressed by a spring r against the rails m. As soon as one of the stops g enters into engagement with the knife b same is carried along by the respective table in the direction of its travel and at the same time drops into the gap h dividing the sheet of glass supported by the tables. Thereby the glass band is completely cut through and an injury of the knife and the support is avoided. The knife b is provided with two blades b¹ and b², through which slips of little breadth are cut out of the band of glass being in plastic condition.

As the slips of glass fall down through the interstices a uniting along the cutting lines after the cutting operation is avoided. In order to limit the downward movement of the knife, there may be arranged below the knife in its cutting plane a resilient spring support s onto which the knife falls at the end of its cutting stroke. This resilient support which acts as a shock absorber, prevents the knife from being injured or even destroyed by striking for instance on the track on which the tables are travelling. The movement of the tables a and the rolling process itself are in no way interrupted by the cutting operation of the knife b, but same is caused to slide on the shaft c in the direction of travel of the tables because it is carried along by the said stop g. After the cutting operation has been termi-

nated, the roller *d* carried by the knife *b* enters into engagement with the inclined plane *e* and gradually ascends the same, whereby the knife *b* is lifted out of the gap *h*. When the knife *b* has been raised in this way out of the gap *h* to such an extent that the roller *i* may run back over the stop *g*, the knife *b* is retracted by the weight *f* along the shaft *c* into its initial position. It will then rest again by its roller *i* on the lateral rail *m* of the table, and it will be released again upon the stop *g* of the succeeding table striking against it. As mentioned above, the knife rests by its roller *i* on the rails *m* when it is in its lifted position. In order to prevent the knife from falling down when the last table has moved past it, a clutch coupling *n* is provided which holds the knife in its lifted position in this case. The clutch coupling *n* consists of a fast clutch member *n*¹ fixed to the shaft *c* and a movable clutch member *n*² fixed to the knife *b*. In the initial position of the knife *b* the two clutch members are engaged and the drop knife *b* is correspondingly held in its raised position (Fig. 3). A soon as the knife *b* has been moved for a little distance by the stop *g*, the clutch coupling is disengaged (Figs. 4 and 5) so that the knife *b* is free to drop and to be raised afterwards.

After the glass plates carried by the tables *a* have been inserted into the annealing kiln, the tables *a* have to be moved back for receiving and feeding further plates. During this return travel of the tables and the knife is further prevented from dropping into the gaps *h* between the tables by the bridging members *p*. These members *p*, when striking against the stop *o* during the return travel of the tables, are swung by this stop into a position in which they bridge the gap *h* in such a manner that the roller *i* running on the rails *m* cannot drop into the said gap. The knife *b* is therefore automatically maintained in its lifted position during the return travel of the tables.

It is of course apparent that as the knife is operated between the last two tables it will return to normal position before the end of the last table passes the knife. In this position the clutch members will be engaged holding the knife elevated until the tables again start to move in the proper direction past the knife. It is of course understood that the knife is released for operation only at the front end of the advancing table, as only the front ends of the tables carry the stop *g*.

Having thus described my invention, what I claim as new and desire to secure by Letters Patent, is:—

1. A device for cutting sheet glass, comprising in combination a conveyor for the sheet glass, a drop knife arranged for sliding movement in the direction of travel of the conveyor at one side thereof, knife supporting rails at one of the longitudinal edges of

the conveyor, transverse interstices in the conveyor and in the knife supporting rails into which the knife is adapted to drop for cutting the sheet glass, and means on the conveyor for engaging the knife and carrying it along with the conveyor during the cutting operation. 70

2. A device for cutting sheet glass, comprising in combination a sheet glass conveyor, a shaft arranged parallelly of the conveyor, a drop knife mounted for swinging and sliding movement on this shaft, rails on one of the longitudinal edges of the conveyor for supporting the knife in its lifted position during the travel of the conveyor, transverse interstices in the conveyor and in the knife supporting rails into which the knife is adapted to drop for dividing the sheet glass, and stops on the conveyor for engaging and carrying the knife along with the conveyor during the cutting operation. 75

3. In a device for cutting sheet glass, a sheet glass conveyor, a drop knife arranged for sliding movement parallel of the conveyor at one side thereof, knife supporting rails on one of the longitudinal edges of the conveyor, transverse interstices in the conveyor and in the knife supporting rails into which the knife may drop for cutting the sheet glass, stops on the conveyor designed to carry the knife along with the conveyor during the cutting operation, means for automatically lifting the knife out of the said interstices after the cutting and means for returning the knife into its initial position. 90

4. In a device for cutting sheet glass, a sheet glass conveyor, a drop knife arranged for sliding movement parallel of the conveyor at one side thereof, knife supporting rails on one of the longitudinal edges of the conveyor a roller carried by the knife and designed to run on the said supporting rails for normally holding the knife in its lifted position, transverse interstices in the conveyor and knife supporting rails into which the knife may drop for cutting the sheet glass, stops on the conveyor designed to carry the knife along with the conveyor during the cutting operation, means for automatically lifting the knife out of the said interstices after the cutting and means for returning the knife into its initial position. 105

5. In a device for cutting sheet glass, a sheet glass conveyor, a drop knife arranged for sliding movement parallel of the conveyor at one side thereof, knife supporting rails on one of the longitudinal edges of the conveyor for normally holding the knife in its lifted position, transverse interstices in the conveyor and knife supporting rails into which the knife is adapted to drop for cutting the sheet glass, stops on the conveyor for carrying the knife along with the conveyor during the cutting operation, an inclined plane arranged so as to co-operate with the knife for 110

- lifting it out of the said interstices and above the said stops after the cutting, and a weight connected with the knife for returning it into its initial position after it has been raised out of the interstices.
- 5 6. A device for cutting sheet glass, comprising in combination a plurality of travelling sheet glass receiving and conveying tables, a drop knife arranged for sliding movement in the direction of travel of the tables at one side thereof, a knife supporting rail on one of the longitudinal edges of each of the tables for normally holding the knife in its lifted position, gaps between the several successive tables and their knife supporting rails into which the knife is adapted to drop for cutting the sheet glass carried by the tables, stops on the tables for engaging and carrying the knife along with them during the cutting operation, and means for lifting the knife out of the said gaps and returning it into its initial position after the cutting.
- 10 7. A device for cutting sheet glass, comprising in combination a plurality of travelling sheet glass receiving and conveying tables, a drop knife arranged for sliding movement in the direction of travel of the tables at one side thereof, a knife supporting rail on one of the longitudinal edges of each of the tables for normally holding the knife in its lifted position, gaps between the several successive tables and their knife supporting rails into which the knife is adapted to drop for cutting the sheet glass carried by the tables, stops on the tables for engaging and carrying the knife along with them during the cutting operation, means for lifting the knife out of the said gaps and returning it into its initial position after the cutting,
- 15 8. A device for cutting sheet glass, comprising in combination a plurality of travelling sheet glass receiving and conveying tables, a drop knife arranged for sliding movement in the direction of travel of the tables at one side thereof, a knife supporting rail on one of the longitudinal edges of each of the tables for normally holding the knife in its lifted position, gaps between the several successive tables and their knife supporting rails into which the knife is adapted to drop for cutting the sheet glass carried by the tables, stops on the tables for engaging and carrying the knife along with them during the cutting operation, means for lifting the knife out of the said gaps and returning it into its initial position after the cutting,
- 20 9. In a device for cutting sheet glass, a sheet glass conveyor, a drop knife arranged for sliding movement parallel of the conveyor, knife supporting rails on the longitudinal edges of the conveyor and means for yieldingly pressing the knife against the supporting rails.
- 25 10. A device for cutting sheet glass, comprising in combination a sheet glass conveyor, a drop knife mounted for sliding movement, rails on the conveyor for supporting the knife in its lifted position during the travel of the conveyor, transverse interstices in the conveyor and in the knife supporting rails into which the knife is adapted to drop for dividing the sheet glass and a shock absorbing support upon which the knife falls at the end of its stroke.
- 30 11. In combination with a conveyor for sheet glass having a series of transverse spaces underlying the glass, a knife mounted for pivotal and sliding movement at one side of the conveyor and in its pivotal movement cutting through the glass in line with one of said transverse spaces, means for holding the knife against pivotal movement, means on the conveyor for releasing the knife from the holding means, means for moving the knife with the conveyor following the cutting operation, means for swinging the knife free of the conveyor following a predetermined sliding movement of such knife, and means for returning the knife to and within the influence of the holding means following the predetermined sliding movement of such knife.
- 35 12. In combination with a conveyor for sheet glass having a series of transverse spaces underlying the glass, a knife mounted for pivotal and sliding movement at one side of the conveyor, and in its pivotal movement cutting through the glass in line with one of said transverse spaces, means for holding the knife against pivotal movement, means on the conveyor for releasing the knife from the holding means, means for moving the knife with the conveyor following the cutting operation, means for swinging the knife free of the conveyor following a predetermined sliding movement of such knife, and means for returning the knife to and within the influence of the holding means following the predetermined sliding movement of such knife.
- 40 13. In combination with a conveyor for sheet glass having a series of transverse spaces beneath the glass, a knife mounted for pivotal movement and bodily sliding movement, means for holding the knife in normal position above the conveyor, means on the conveyor to release the knife from its holding means and permit the operative pivotal movement of the knife to cut the glass in line with one of said transverse spaces, and means for automatically restoring the knife to a normal position and within the influence

of its holding means, said knife comprising spaced parallel plates.

14. In combination with a conveyor for sheet glass having a series of transverse spaces beneath the glass, a knife mounted for pivotal movement and bodily sliding movement, means for holding the knife in normal position above the conveyor, means on the conveyor to release the knife from its holding means and permit operative pivotal movement of the knife to cut the glass in line with one of said transverse spaces, said knife being bodily moved with the conveyor following the cutting operation, a member adapted to elevate the knife above the conveyor following a pre-determined bodily movement thereof, means for compelling a bodily movement of the knife when elevated toward normal position and within the influence of the holding

20 means, and a track on the conveyor supporting the knife during operation of said last mentioned means.

15. The combination with a moving conveyor for sheet glass having transverse open spaces along its length, of a knife mounted for down movement to cut through the glass in line with said open spaces and for movement with the conveyor following such cutting operation, means actuated from the conveyor for moving the knife with the conveyor, means for lifting the knife to a position free of the conveyor following a predetermined movement of the knife with the conveyor, and means for then returning the knife to normal position irrespective of further movement of the conveyor.

16. In a device for cutting glass sheets, the combination with a traveling conveyor having transverse open spaces along its length of a knife mounted for vertical movement and also for movement with the conveyor, means tending to depress the knife, means tending to hold the knife adjacent to one end of its path of movement with the conveyor, means moving with the conveyor and contacting with the knife to maintain the latter raised during the period of such contact, driving means for the knife moving with the conveyor and engaging the knife when the latter is lowered, and means brought into action by the travel of the knife for raising the knife to a position beyond the influence of the knife driving means.

17. The combination with a traveling conveyor for sheet glass having transverse open space lengths along its length, of a knife mounted for vertical motion and for movement with the conveyor, means on the conveyor for normally holding the knife in an elevated position adjacent to one end of its path of travel with the conveyor, means for driving the knife horizontally with the conveyor when moved from its upper position, means actuated by the travel of the knife to

raise the knife when adjacent to the other end of its path of travel to a position beyond the influence of the driving means, and means for restoring the knife to its normal position

In testimony whereof I have signed my 70 name to this specification.

LAMBERT VON REIS.
